UNITED STATES PATENT OFFICE.

ABNER K. WOLFE, OF ATCHISON, KANSAS, ASSIGNEE OF ONE-HALF TO CLEMENT DAVIS, OF RULO, NEBRASKA.

SIDE BEARING.

1,108,054.

Specification of Letters Patent. Patented Aug. 18, 1914.

Application filed February 12, 1913. Serial No. 748,003.

To all whom it may concern:

Be it known that I, ABNER K. WOLFE, a citizen of the United States, residing at Atchison, in the county of Atchison and State 5 of Kansas, have invented a new and useful Side Bearing, of which the following is a specification.

The invention relates to side bearings for trucks of street cars and railway cars.

10 The object of the present invention is to improve the construction of side bearings, more especially that shown and described in Patent No. 1,031,761, granted to me July 9, 1912, and to provide a simple, inexpensive 15 and easily manufactured side bearing, designed for use on the trucks of both street cars and railway cars, and adapted to eliminate the spider frames of the aforesaid patent, and equipped with means for enabling 20 it to be readily adjusted both in the preliminary adjustment or positioning of the parts of the side bearing and also to take up wear and obviate the necessity of cutting shimming plates for this purpose.

25 With these and other objects in view, the invention consists in the construction and novel combination of parts hereinafter fully described, illustrated in the accompanying drawings, and pointed out in the claims 30 hereto appended; it being understood that various changes in the form, proportion, size and minor details of construction, within the scope of the claims, may be resorted to without departing from the spirit or sacrificing any of the advantages of the invention.

In the drawings:—Figure 1 is a side elevation of a side bearing, constructed in accordance with this invention and shown applied to a portion of a street car truck. Fig. 2 is a horizontal sectional view of the same. Fig. 3 is a front elevation of the truck, the side bearings being in section. Fig. 4 is a vertical sectional view on the line 4—4 of Fig. 3. Fig. 5 is a detail perspective view of the upper bearing plate. Fig. 6 is a similar view of the lower bearing plate. Fig. 7 is a detail perspective view of one of the adjustable wedge-shaped plates. Fig. 8 is a perspective view of a side bearing designed for use on the trucks of railway cars.

Like numerals of reference designate corresponding parts in all the figures of the drawings.

55 In the accompanying drawings in which is

illustrated the preferred embodiment of the invention, the side bearing comprises in its construction upper and lower bearing plates 1 and 2, secured, respectively, by vertical bolts 3 and 4 to an upper body bolster 5 and a lower truck bolster 6 and curved longitudinally and provided with arcuate grooves 7 and 8 formed in the lower face of the upper bearing plate and in the upper face of the lower bearing plate and receiving antifriction rollers 9. The arcuate grooves 7 and 8 form a runway for the antifriction rollers, and each groove has a greater depth in the center and is provided with inclined approaches presenting a concave contour 70 viewed longitudinally as in Fig. 4 of the drawings. The upper bearing plate is preferably provided at the sides and ends of its groove with depending flanges, but the groove of the lower bearing plate is preferably open at the front at 10.

Any number of antifriction rollers, which are in the form of truncated cones, may be employed, but when the side bearing is designed for use on street cars, they are preferably arranged in pairs and tied together by approximately U-shaped yokes 11. Each yoke 11 consists of straight divergent side portions and an inner connecting portion, and it is adapted to maintain the rollers in proper relative position and it assists their return to a position centrally of the side bearings. The sides of the yoke extend through central openings in the antifriction rollers from the inner ends thereof, the connecting 90 portion being located at the inner sides of the bearing plates. The outer terminals of the side portions of the yoke are provided with perforations for the reception of keys 12, or other suitable fastening devices for retaining the sides of the yoke in the openings of the antifriction rollers.

Under normal circumstances when the two bolsters are in parallel relation, the weight of the car is supported by the rollers 100 and by the center bearing 13, as clearly shown in Fig. 3 of the drawings. Under such circumstances, the antifriction roller occupies the position illustrated in Figs. 1 and 4 in the deepest portion of the runways 105 of the bearing plates, but when a curve is reached and the truck bolster swings to a position at an angle to the body bolster, the antifriction roller will travel up the inclined or bearing face of the lower bearing plate, 110

thus lifting the body bolster 5 with its center plate 14 out of contact with the plate 15 of the truck bolster 6 throwing the entire load on the side bearings and relieving the center bearing while the car is rounding a curve. As soon as the car leaves a curve, the truck returns to its normal position through gravity.

In order to enable the bearing plates to be properly adjusted to the body and truck bolsters in assembling the parts and also to enable wear of the parts to be readily taken up without the trouble and inconvenience of cutting shimming plates, the lower bearing plate is provided with tapered or wedge-shaped end portions 16, presenting lower inclined faces 17 and provided with transverse corrugations 18 at the inner portions of the said inclined faces 17. The corrugated inclined bottom faces of the lower bearing are engaged by adjustable wedges 19, consisting of tapered or wedge-shaped plates or pieces having horizontal lower faces to fit the upper face of the truck bolster and presenting inclined upper faces, which are provided with corrugations 20 to engage the corrugations of the lower bearing plate. The adjustable wedges are provided with vertical longitudinal slots 21, extending inwardly from the outer end edges of the wedges and terminating short of the inner ends of the same and receiving the lower vertical bolts 4, which fasten the lower bearing plate to the truck bolster and secure the wedges in their adjustment. The interlocking of the wedges with the lower bearing plate prevents any liability of the wedges accidentally slipping especially when the weight is shifted to and solely sustained by the side bearings. By adjusting the wedges inwardly and outwardly, the lower bearing plates may be raised and lowered, and the wedges are also susceptible of independent adjustment to level the lower bearing plate or otherwise properly position the same. Both the upper and lower bolts 3 and 4 are preferably provided with square heads, which are seated in recesses in the grooved faces of the upper and lower bearing plates.

The form of side bearing illustrated in Figs. 1 to 7 inclusive is designed particularly for street car service, but the improvements are equally applicable to side bearings of railway car trucks, and in Fig. 8 of the drawings is illustrated a railway car truck side bearing in which only a single antifriction roller 22 is employed. The upper bearing plate 23 is provided with enlarged side flanges 24, having longitudinal slots 25 in which operate central or axial projections 26 of the antifriction roller 22. The axial projections 26, which are loose in the slots 25, may be formed in any suitable manner, such as by securing within the central opening a continuous pin of a length to extend

entirely through and project beyond the roller, but screws or any other similar means may be employed. These projections 26 are adapted to prevent displacement of the antifriction roller. The upper bearing plate 23 and the lower bearing plate 27 have concave faces 28 and 29 to coact with the antifriction roller, and the lower bearing plate is provided with adjusting means similar to those heretofore described, the terminal portions 30 of the lower bearing plate being tapered or wedge-shaped and presenting lower inclined corrugated faces 31 to engage with upper inclined corrugated faces 32 of adjustable wedges 33. The wedges 33 are provided with longitudinal slots 34 and are secured in their adjustment by bolts 35, which fasten the lower bearing plate to the truck bolster 36.

What is claimed is:—

1. The combination with body and truck bolsters, of a side bearing including an upper bearing plate secured to the body bolster, a lower bearing plate having tapered or wedge-shaped end portions presenting lower inclined faces, the intermediate portion of the lower bearing plate having a horizontal lower face to fit against and rest upon the truck bolster, an antifriction device interposed between the upper and lower bearing plates, and adjustable wedges arranged upon the truck bolster beneath the end portions of the lower bearing plate and presenting upper inclined faces to the latter and supporting the same, said wedges being movable with respect to the lower bearing plate and adapted to raise and lower the same without affecting the relative arrangement of the said bearing plates.

2. The combination with body and truck bolsters, of a side bearing including an upper bearing plate secured to the body bolster, a lower bearing plate having tapered or wedge-shaped end portions presenting lower inclined faces, the intermediate portion of the lower bearing plate having a horizontal lower face to fit against the truck bolster, an antifriction device interposed between the upper and lower bearing plates, and adjustable wedges arranged upon the truck bolster beneath the end portion of the lower bearing plate and presenting upper inclined faces to the same, said wedges supporting the end portions of the lower bearing plate and movable on the truck bolster and adapted to raise and lower the lower bearing plates without affecting the relative arrangement of the said bearing plates, and fastening devices piercing the end portions of the lower bearing plate and the wedges and securing the former to the truck bolster and the wedges in their adjustment.

3. The combination with body and truck bolsters, of a side bearing including upper

- and lower bearing plates, the upper bearing plate being secured to the body bolster and the lower bearing plate having tapered end portions presenting lower inclined faces,
- 5 an antifriction device interposed between the upper and lower bearing plates, wedges arranged on the truck bolster and located beneath the end portions of the lower bearing plate and presenting inclined faces to
- 10 the same and adjustable with respect to the lower bearing plate and adapted to raise and lower the same without affecting the relative arrangement of the said bearing plates, said wedges being also provided
- 15 with longitudinal slots extending inwardly from the ends of the wedges, and fastening devices piercing the end portions of the lower bearing plate and extending through the slots of the adjustable wedges to secure the former to the truck bolster and retain the wedges in their adjustment.
4. The combination with body and truck bolsters, of a side bearing including upper and lower bearing plates, the upper bearing plate being secured to the body bolster and the lower bearing plate having tapered end portions presenting lower inclined
- transverse faces and provided with transverse corrugations, the intermediate portion of the lower bearing plate having a smooth 30 horizontal lower face to rest upon the truck bolster, an antifriction device interposed between the upper and lower bearing plates, wedges arranged upon the truck bolster and located beneath the end portion of the lower 35 bearing plate and presenting inclined upper faces having corrugations to interlock with the corrugations of the lower bearing plate, said wedges being adjustable and adapted to raise and lower the bearing plate without 40 affecting the relative arrangement of the said bearing plates, and fastening devices piercing the end portions of the lower bearing plate and the wedges and securing the former to the truck bolster and retaining 45 the wedges in their adjustment.
- In testimony, that I claim the foregoing as my own, I have hereto affixed my signature in the presence of two witnesses.
